UNITED STATES PATENT OFFICE.

ARTHUR DE LATHAUWER, OF FLAWINNE, BELGIUM.

MEANS FOR BRAKING RAILWAY VEHICLES.

Application filed December 5, 1922. Serial No. 605,123.

To all whom it may concern:

Be it known that I, ARTHUR DE LATHAUWER, subject of Belgium, residing at 187 Rue de la Station, Flawinne, Belgium, have invented certain new and useful Improvements in Means for Braking Railway Vehicles, of which the following is a specification.

This invention relates to apparatus for 10 braking railway vehicles, of the kind comprising a pair of braking bars adapted to be mounted between the rails of a railway track and mechanism for moving apart said braking bars so that they will engage the 15 inner faces of the vehicle wheels, and thus check or stop the progress of such vehicles. Various types of such apparatus have been designed for use in braking railway cars and more particularly colliery cars, 20 trucks and light wagons, but considerable difficulties arise in practice when such apparatus are intended for use on standard gauge railways on account of the enormous stresses to which they are subjected when 25 acting on heavily loaded cars and trucks.

The object of my present invention is to provide a braking apparatus of this kind which is of such strength and in which the movable parts are so firmly guided that 30 said apparatus will be particularly suitable for use on standard gauge railways as for example in carrying out shunting operations when making up trains.

In order that my invention may be better 35 understood reference will be had to the accompanying drawings which show, by way of example, an apparatus constructed in accordance therewith, and in which:

Figure 1 is a diagrammatic plan view of 40 the entire apparatus.

Figure 2 is a transverse section on a larger scale taken on the line A—B of Figure 1.

Figure 3 is a plan, to the same scale as 45 Figure 2, of a wedge and the adjacent struts.

Figure 4 is a section taken on the line C—D of Figure 3.

Figure 5 is an elevation of the controlling 50 means.

In the drawings the rails of the permanent way or track are marked 1, the braking bars 2, their struts 3 and the wedges 4. The braking bars 2 are formed of rails laid 55 parallel to the permanent way (Figures 1 and 2) with their heads facing the side of

each rail 1. To the shoe of each of the rails are fastened the struts 3 formed by transverse bars terminated near the axis of the track by inclined surfaces between 60 which are the wedges 4.

The struts 3 and the wedges 4 rest upon transverse girders 5 fastened to wooden soles 6 placed longitudinally and fixed upon the sleepers 7 of the track to form a supporting frame for the braking mechanism. The rails or braking bars 2 rest, by means of liners or supporting blocks 8, upon metal plates 9 fixed to the soles 6, in alignment with the girders or beams 5.

Into each plate 9 there is screwed a bolt 10 (Figure 2) which extends through a groove 11 formed in the lining 8 and the rail 2 and carries a nut 12 intended to prevent the lifting of the braking rail 2 while 70 allowing the latter to move laterally to a distance equal to the length of the groove 11.

The struts 3 are, furthermore, held against the girders 5 by yokes 13 riveted to the girders and forming, with the latter, 80 slideways for the struts. Upon the yokes 13 near to the wedge 4 there is riveted a transverse yoke 14 to the centre of which is secured a pin 15 (Figures 3 and 4) which penetrates a vertical groove 16 formed in 85 the wedge 4 (Figure 3) to guide the latter so that it will exert equal pressure upon the struts on either side thereof.

The operation of the wedges may be effected by means of chains or cables or, as 90 shown, by a set of rods and levers comprising short rods 17 pivoted at 18 to the ends of the wedges (Figure 1), bell-crank levers 19 and rods 20 and 21 with regulating sleeves 22. The rods 21 (Figure 5) are 95 pivoted to the bottom of a lever 23 pivoted at 24 to a supporting frame 25 and at its upper end to an internally threaded sleeve 26 mounted upon a screw provided with an operating hand-wheel 28.

If the handwheel 28 be so operated as to displace the rods 21 in the direction of the arrow (Figure 1) the wedges will move apart the struts 3 with the braking bars 2 and these latter will approach the rails 1 105 so as to exert upon the inner faces of the wheels 29 (Figure 2) a more or less powerful braking effect according to the degree to which they are approached thereto. The braking bars or rails 2 are bevelled at 30 110 (Figure 1) so as to avoid shocks at the entrance of the apparatus. An operation of

the handwheel 28 in the opposite direction will return the wedges to the rear. The struts and the braking bars will then remain in their braking position, but will no longer 5 be subjected to the pressure of the wedges so that the first vehicle passing will push them back, without appreciable resistance, into the position shown in the drawings. In Figure 1 two rods 21 are shown, abutting 10 upon the lever 23 so that one of these rods always works with a tractive action when the handwheel is operated.

The apparatus shown may be of any 15 length, but it is advisable to give the locking bars 2 a sufficient length to act upon at least two sets of wheels at a time. The use of this apparatus enables all manœuvres of rolling stock to be facilitated and accelerated without danger, as it is of safe and efficacious 20 operation and cannot be displaced from the permanent track. When the inclination of the terrain lends itself thereto it affords means of effecting the manœuvres without the employment of a locomotive. In all 25 these cases the use of the apparatus permits of the realization of a considerable economy of time and labour. Finally the apparatus can be placed upon main lines and connected to the controls of the signals by means of 30 known connection so as to slow down or stop trains in the event of the latter overrunning the signals when the same are in the "danger" position.

It will be understood that various modifications may be applied to the apparatus described without departing from the scope of the invention. Thus, for example, instead of moving the braking bars apart by means of wedges, the rods 17 may, when no great 40 power is required, be pivoted to bars 31 (Figure 6) pivoted in their turn to the braking bars 2 and acting in the same way as a toggle to push the bars 2 outward.

I claim:

45 1. In combination with a railway track, a pair of braking bars arranged between the rails of said track and parallel thereto, a plurality of pairs of inwardly extending struts having their outer ends connected to said braking bars, a corresponding number of centrally located wedges adapted to be driven each between the inner ends of a pair of struts, pivoted links connecting said wedges with each other, means for pulling

said wedges axially of the track, and means 55 including pin and slot connections for guiding said wedges.

2. In combination with a railway track, an understructure secured to the sleepers of said track, said understructure comprising a 60 pair of longitudinal soles and transverse girders connecting said soles with each other, a pair of braking bars arranged between the rails of said track and parallel thereto, a plurality of pairs of inwardly extending 65 struts resting each on one of said girders and having their outer ends connected to said braking bars, a corresponding number of centrally located wedges adapted to be driven each between the inner ends of a pair 70 of struts, pivoted links connecting said wedges with each other, means for pulling said wedges axially of the track, guiding means for said bars comprising pin and slot connections between said bars and soles, 75 guiding means for said struts comprising yokes secured to said girders, and guiding means for said wedges comprising yokes secured to said girders and pin and slot connections between the last-mentioned yokes 80 and said wedges.

3. In combination with a railway track, an understructure secured to the sleepers of said track, a pair of braking bars arranged between the rails of said track and parallel 85 thereto, a plurality of pairs of inwardly extending struts resting on said understructure and having their outer ends connected to said braking bars, a corresponding number of centrally located wedges adapted to be 90 driven each between the inner ends of a pair of struts, pivoted links connecting said wedges with each other, guiding means on said understructure including pin and slot connections with said wedges, and means for 95 pulling said wedges axially of the track comprising links pivoted to the foremost and rearmost wedges, a pivoted lever on the side of the track, a pivotal connection between the last mentioned links and said lever, a 100 nut pivotally connected to said lever, and an operating screw engaging said nut.

In testimony whereof I have affixed my signature in presence of two witnesses:

ARTHUR DE LATHAUWER.
